UNITED STATES PATENT OFFICE.

HENRY C. BUCHWALD AND JOSEPH H. CONNELLY, OF BALTIMORE, MARYLAND.

SLUG-CASTING MACHINE.

1,360,881.

Specification of Letters Patent. Patented Nov. 30, 1920.

Application filed November 15, 1916. Serial No. 131,515.

To all whom it may concern:

Be it known that we, HENRY C. BUCHWALD and JOSEPH H. CONNELLY, citizens of the United States, residing at Baltimore city 5 and State of Maryland, have invented new and useful Improvements in Slug-Casting Machines, of which the following is a specification.

This invention has reference to means for 10 adjusting the slug space of a line casting mold in connection with machines of the Mergenthaler type, and consists primarily in means whereby such space may be adjusted both as to length and thickness with- 15 out disturbance of any of the standing parts of the machine. The improvement is illustrated as being applied to a machine employing the particular slug trimming adjusting means of the Kennedy Patent No. 20 1,002,281, though with slight modification it may be applied to machines employing other types of trimmer adjusting mechanism.

In the drawings,—Figure 1 is a front elevation of a portion of the mold carrier wheel, with the mold cap adjusting means and liner inserting means in operative relation with the mold thereof. Fig. 2 is a detail view of one of the liner inserting elements. Figs. 3 and 4 are diagrams illustrating various relative arrangements of the liners and liner inserting elements. Fig. 5 is a horizontal sectional view through typical slug trimming mechanism and mold carrier wheel with the present improvements applied thereto. Fig. 6 is a detail view of one of the mold cap locking elements. Fig. 7 is a horizontal sectional view through the mold carrier wheel illustrating the means 30 for locking and unlocking the mold cap. Fig. 8 is a front elevation of one form of flexible liner. Fig. 9 is rear elevation of the slug trimming mechanism with the present invention mounted thereon and having parts 35 broken away for clearness.

Fig. 10 is a transverse section through the carriage 51 and some of the related parts taken as through the center of the link 56 in Fig. 9 and viewed looking toward the 40 bottom of the sheet.

Referring to the drawings, 1 represents the fixed blade and 2 the adjustable blade of a slug trimmer, the latter being secured by bolts 3 to the slide which is composed of 45 parts 4 and 5 secured together by bolts 6. Said slide is normally pressed in one direc-

tion by the usual spring 7 maintaining the stud 8 in contact with one of the usual screws 9, said screws projecting different distances beyond the face of sector plate 10, 60 so that as the plate 10 is turned one after the other of the screws 9 will be brought into engagement with the stud 8, thereby modifying the separation of the cutter blades 1 and 2. A handle 11 with usual indicator 65 12 is provided for turning said sector plate 10. The mold carrier wheel 14 is of typical form and has the usual geared periphery 15 and fixed mold part 16. Within the usual cut-out portion 17 is arranged the adjustable 70 mold cap 18 which in the present improvements carries the guide pins 19 and 20. The cap 18 is held in adjusted position by spring pressed pins 21 provided each with a transverse opening 22 receiving a coil spring 23 75 and spring pressed plate 24, the latter for pressing said pin in a direction to cause its teeth or threads 25 to engage, in a manner similar to that of a ratchet pawl, the threads of a screw 26 which passes through the said 80 opening 22. The screws 26 pass through the mold carrier wheel 14 and into the mold cap and are prevented from longitudinal displacement by pins 27 entering grooves 28 in said screws. This construction constitutes a preferred type of ratchet locking 85 means or device. By rotating the screws 26 slightly the adjustment may be corrected to coincide with type measure, it being understood that the threads of screw 90 26 and the teeth 25 are spaced according to type measure and through wear or carelessness may require correction. One end of the slug space of the mold is closed by the usual extension 29 of the fixed mold part 16 95 while the opposite end is closed by one or more of a series of flexible liners 30, 31, 32, 33, said liners each comprising an integral piece of metal or being composed of a plurality of jointed sections as illustrated in 100 Fig. 8, in either case the advance end thereof being provided with a pair of extensions 34 and an intermediate notch 35 to facilitate entrance into the slug space in a manner to be described. The jointed sections 36 of Fig. 105 8 are illustrated as being connected in series by flexible strips 37 dovetailed together, but obviously these sections may be hinged together. The mold carrier wheel face is recessed as at 38 to serve in conjunction with 110 the housing 39 and guard 40 to house the series of liners, the housing so formed ex-

tending substantially concentrically with the mold wheel and the portion adjacent the entrance to the slug space of the mold being deflected to substantially aline therewith. 5 Were the liners not so housed or were they rigid and not flexible, they would, owing to their increased length, project beyond the periphery of the mold wheel when not entered sufficiently into the slug space, and 10 thereby interfere with proper operation of certain mechanism. The mold cap 18 is provided with a shoulder 41 substantially equal in width to the combined thickness of all and at least of all but one of the liners and this shoulder acts as a stop to prevent entrance into the slug space of a quantity of 15 liners in excess of the quantity that can be accommodated according to the separation of the mold parts. The ends of the liners 20 not admitted to the slug space are accommodated in the cut-out portion 42 of the mold cap, the said guide pin 20 of the mold cap preventing the liners from complete withdrawal from between the mold parts 25 through its being passed through longitudinal slots 43 in the liners as illustrated in Fig. 8. The guard 40 in addition to closing the opening 38 of the liner housing, also closes in the usual manner the opening between the mold cap and mold wheel flange 15.

Reverting to the trimmer mechanism, the part 4 of the knife adjusting slide is provided with the usual spaced pillars 44 through which pass the usual knife bearing screws 45. Secured to each of these pillars 44 by bolts 46 are slideways 47 in parallelism as illustrated in Fig. 9, said ways having right angular ears 48 through which the bolts 46 pass. These ways 47 have beveled inner edges to receive the beveled edges of a plate 49, the latter being secured to a block 50 provided on one side of a carriage 51. Adjacent the carriage 51 is a screw housing 52 provided with a slide plate 53 operating between slide ways 54 provided on the carriage 51. The plate 49 has a stop extension 55 with which the slide plate 53 engages when the screw housing 52 is in the proper position 50 with reference to the carriage 51, as illustrated in Fig. 10. To the block 50 is secured a link 56 having connection with a lever 57 pivoted at 58 to an extension 47^a of one of the ways 47. Said lever 57 having a 55 spring pressed pin 59 adapted to enter either of the openings 60, 61 to lock the lever where adjusted. The said slide 4 for the slug trimmer blade 2 is not only provided with said pillars 44, but intermediate these it is 60 also equipped with a lug 62 which is split as shown in Fig. 10 to receive a bow-shaped spring 63 which is commonly employed for attachment with the adjustable trimmer blade 2 to urge the latter against the adjusting screws 45 of the pillars 44. When the

said lever 57 is operated to bring its pin 59 into opening 61 of the extension 47^a, the carriage 51 is drawn away from the trimmer blade 2, and with it carrying the other attached mechanism to be described from between the trimmers 1 and 2 and the linotype mold to permit competent operation of the trimming and casting mechanism. When the said lever 57 is moved to cause its locking pin 59 to enter opening 60, the carriage 70 75 70 assumes the position illustrated in Figs. 5 and 10, and it will be noted that the said stop extension 55, as illustrated in Fig. 10, engages with the said lug 62 thereby producing a fixed relation of the carriage 51 80 and its associated mechanism with the trimmer slide 4 and its associated mechanism.

The said screw housing 52 which is carried by the carriage 51 has within its interior a quick acting screw rod 65 which is rotated 85 by a hand wheel 66 and intermediate bevel gears 67, 68, the said hand wheel being in position directly beneath the trimming blade adjusting mechanism to be readily grasped by the operator. Upon the screw 65 is a nut 69 having an arm 70 extending through the longitudinal slot 71 in one wall of the housing 52. This arm 70 as shown in Fig. 2 is provided with a series of feeler openings 72 through which some of the fingers 73, 75, of 90 feeler plates 76, 77, 78, 79 extend. Secured upon the arm 70 is a cap 80, between which and the said arm 70 space is provided as illustrated in Fig. 2 for movement of the feelers against the action of springs 81, which 95 latter are secured at one end in the said cap 80 and bear at the other end upon extensions 82 of the feelers. This construction as will be later pointed out permits the fingers 73, 75, of any or all of the feelers to be entirely 100 entered by pressure into the interior of the said arm 70. When the said lever 57 is moved to bring the carriage 51 to the position of Fig. 5, the said feelers will be brought over or rather into the proper position with reference to the slug space of the linotype mold, and provision is made for moving them as a whole against the said mold, such provision being in the nature of a crank shaft 85 bearing against the said 105 screw housing 52 and having its ends journaled in bearings 86 on the said carriage 51, one end of said crank shaft having a lever 88, which when operated causes the screw housing 52 to be moved out from the Fig. 10 110 position to the Fig. 5 position against the action of a returning spring 89, a suitable locking device 90 being provided for locking said lever 88 in either its depressed or elevated positions. For engaging the screw 115 housing 52 with the mold cap 18, the former is provided with a rib 91 which enters a groove 92 formed in the mold cap, and when so entered depresses the locking pins 21 so that the mold cap may be moved for desired 120 125 130 130

adjustment with respect to the fixed mold part.

The fixed mold part 16 is preferably provided with a notch 98 and outwardly rising 5 incline 99 for a purpose to be set forth in connection with the complete operation of the invention.

Referring to Fig. 3, the same is a diagram showing how certain feelers go out of action 10 as certain liners are prevented from entering the mold. As liner 33 is excluded, feeler 79 goes out of operation; and so on, feeler 32 with liner 78; feeler 77 with liner 31; and feeler 76 with liner 30. It will be observed 15 that feeler 77 and liner 31 are of less gage than the other feelers and liners, which latter are to the same gage, and this is to permit any desired adjustment of the slug space according to type gage, the mechanism 20 constituting a preferred type of means having a step adjustment bearing the proper relation to the ratchet locking device. For instance liner 31 and feeler 77 are say two points, and the other liners and feelers four 25 points, and it will be observed that the arrangement is such that the liners and feelers of the same gage go out of action up to a certain point, and then it will be found that a four point liner is engaged by a two 30 point feeler and a part of a four point feeler, but when it is remembered that the difference is made up by the other part of said four point feeler being engaged by the remaining two point liner there is no discrepancy 35 as it is not essentially the number of feelers which act with the liners, or even the number of liners which act with the feelers, but rather the combined gage or thickness of the combined liners acting with 40 feelers of corresponding combined gage or thickness. So long as the liners run in the same order from the molding face of the fixed mold part that the feelers assume from the molding face of the adjustable mold 45 part, the combined gage or thickness of the feelers acting will be coincident with the combined gage of the liners permitted to enter the slug space. In this connection, the same is true of different arrangements of 50 liners and feelers. As shown in the diagram in Fig. 4 the feelers may all be of two point gage as 100, 101, 102, 103, 104, 105, 106 and the liners of the same gage as in Fig. 3, or the arrangement may be reversed 55 with the liners of one point gage.

The operation is as follows. Assuming that the spaces between the mold parts and the slug trimming blades are of the proper relative sizes and that a slug has just been 60 trimmed, and that it becomes necessary to either change the gage of the next slug as to thickness or to change its length. The usual custom is to open parts of the machine in order to make the required change, but with 65 the present invention, no such practice is

necessary. The operator first grasps the lever 57 moving it so that its locking pin 59 is moved from locking opening 61 into opening 60, and with such movement of said lever, the carriage 51 and its associated 70 parts are caused to move along the ways 47 until arrested by the stop extension 55 coming into contact with the stud 62 of the knife slide 4. When so arrested, it will be understood that the carriage 51 and its associated parts are thereby placed in a fixed relation to the said trimmer slide 4 and its associated parts. In this position, the rib 91 will be juxtaposed to the groove 92 in the mold cap 18 and the feelers 76, 77, 78, 80 79, one or all, will be juxtaposed to the slug space of the mold parts. The operator next throws the lever 88 to cause the crank shaft 85 to move the screw housing 52 with reference to the carriage 51 as illustrated in Fig. 85 5, and the parts are locked in the position shown in Fig. 5 due to the locking device 90 being caused to assume the position clearly shown in Fig. 5. Thus the rib 91 is moved into the mold cap groove 92, and 90 the feelers 76, 77, 78, 79, either moved into the space between the mold parts or into contact with the adjacent face of the fixed mold part and depressed thereby, it being observed that the position for the feeler arm 95 70 is at the entrance end of the slug space with the feeler fingers 75 ready to enter the liner notches 35 prior to such actuation of the crank 88. The operator then actuates the handle 11 of the slug trimmer mechanism to bring the desired screw 9 into engagement with the stud 8 of the slide 4—5, thereby causing movement of the latter and also of the adjustable trimmer blade 2 so that the latter will assume the desired position relative to the fixed trimmer blade 1. Owing to the fixed relation established as aforementioned between the carriage 51 and its associated parts and the trimmer slide 4 and its associated parts, the said carriage and 100 its associated parts are correspondingly moved with the trimmer parts. With such movement, since the rib 91 is entered into the mold cap groove 92 and thereby depressing the mold cap locking pins 21 to 105 unlock the mold cap 18, said rib carries with it the mold cap placing the cap in the proper distance from the fixed mold part 16 to suit the position that the adjustable trimmer blade 2 has or assumes relatively to the fixed 110 trimmer blade 1. Thus, the space between the trimmer blades and the slug space between the mold parts are correlative. In some cases, it may be desirable or necessary to make independent adjustments of 115 the trimmer blade and mold cap, which is permitted by operating the levers accordingly, or the trimmer may be first moved to its desired adjusted position and the lever 57 and crank shaft lever 88 then operated to 120 125 130

cause the rib 91 to find the mold cap groove 92 when further movement of the said lever 57 may be employed to move the parts until contact of the stop extension 55 with the lug 62, the principal point in either method of operation being that when said stop extension 55 engages said stud 62 the operator may know that the molding face of the mold cap 18 bears the proper relation to the trimming edge of the trimmer blade 2.

If it is desired to change only the thickness of the slug the mold cap and adjustable trimmer blade are adjusted in the manner just stated, then the crank shaft lever 88 and carriage moving lever 57 may be operated to return the carriage 51 and its connected parts to retracted position, in which position, the locking pin 59 of said lever 57 will enter the opening 61. With the parts so retracted, the trimming operation may be performed without interference of the parts of this improvement. Should it not, however, be desired to return the parts to retracted position, but to insert or withdraw liners from the mold slug space, the parts are retained in the position described above which is the Fig. 5 position. The operator then rotates the hand wheel 66 causing rotation of the feed screw 65 whereby the nut 69 is caused to move longitudinally of the screw housing 52. As the said nut 69 moves along, its arm 70 carries the feelers 76, 77, 78, 79, along the slug space of the mold, and such fingers 75 of the feelers which have entered the notches 35 of certain of the liners will draw whichever liners as are engaged into the slug space of the mold. Obviously reverse rotation of the feed screw 65 will cause ejection in a similar manner of the liners from the slug space. With the liners all ejected from the slug space, the liner notches 35 all alone so that the alining fingers 75 of the feelers may engage the required number of liners to be entered into the mold. As the mold cap 18 is moved by the rib 91 it increases or decreases the entrance to the slug space so that all or only a part of the number of liners may be admitted, the shoulder 41 of the mold cap 50 acting as a barrier against entrance of liners in excess of the desired number, and in Fig. 1, the undesired liner is liner 33. As the mold cap moves to exclude certain liners, its movement correspondingly causes feelers 55 to be put out of action, and in Fig. 1, it is illustrated as being feeler 79. Such feeler is rendered inactive due to its being placed over or rather beyond the molding face of the fixed mold part 16 so that it is depressed into the arm 70 and only the feelers which may enter the slug space being permitted to act upon the liners which may enter the slug space. When the mold cap is moved to exclude both liners 33 and 32, such movement will also have placed both feelers 60 65

and 78 beyond the molding face of the fixed mold part 16.

The faces of projections 34 of the liners are flush with the outer faces of the fixed and adjustable mold parts, hence when the 7 rib 91 is seated in the groove 92 and the feeler fingers 75 are in position to enter the liner notches 35 and it becomes necessary to diminish the separation of the mold parts, to permit same, the fixed mold part 16 is 75 notched as at 98, Figs. 1 and 5, so that as the feelers are moved over the molding face of the fixed mold part 16 they will move into said notch 98 and later ride up the inclined portion 99, Fig. 1, onto the outer face of the 80 fixed mold part.

After the liners have been adjusted, or after the mold cap has been adjusted, upon withdrawal of the carriage 51, movement of the rib 91 from within the mold cap 85 groove 92 permits said pins 21 to assume normal position with their teeth or threads 25 interlocked with the threads of the screws 26.

Of course it is to be understood that while 90 the invention has herein for the purpose of illustration been applied to a machine of the Mergenthaler type, it is equally intended for any other type or make of line or slug casting machine which has to change the 95 length or thickness of the slug casting space of the mold by the use of liners.

What is claimed is—

1. A slug casting mold having relatively adjustable parts, and a flexible liner between 100 said parts, and a housing for the reception of said liner.

2. A slug casting mold having relatively adjustable parts forming between their molding faces the slug space, and a flexible 105 liner between said molding faces, and a housing for the reception of said liner.

3. A slug casting mold having relatively adjustable parts, and flexible liners in position to be selectively entered between said 110 parts.

4. A slug casting mold having relatively adjustable parts, and flexible liners of different gage in position to enter between said parts, and a housing for the reception of 115 said liners.

5. A slug casting mold having relatively adjustable parts, and flexible liners of different gage in position to be selectively entered between said parts.

6. In a device of the character described, a linotype mold having relatively adjustable parts, a plurality of liners in position to enter between said mold parts and selectively operative means for moving a variable number of said liners between said mold parts.

7. In a slug casting machine, a mold carrier, a mold having relatively adjustable parts forming between their molding faces 130

- the slug space, and a flexible liner movable into the slug space and said liner being of a greater length than the distance between the periphery of the carrier and the entrance to the slug space and being at all times restrained from extending beyond the periphery of said carrier.
8. In a slug casting machine, a mold carrier, a mold having relatively adjustable parts forming between their molding faces the slug space, a flexible liner movable into the slug space, and means for deflecting any uncentered portion of the liner from projecting beyond the periphery of the carrier.
- 15 9. A slug casting mold having relatively adjustable parts forming between their molding faces the slug space, and a sectional flexible liner movable into the slug space.
- 20 10. A slug casting mold having relatively adjustable parts forming between their molding faces the slug space, and a flexible liner comprising connected sections movable into the slug space.
- 25 11. A slug casting mold having relatively adjustable parts forming between their molding faces the slug space, and a flexible liner comprising jointed sections movable into the slug space.
- 30 12. In a slug casting machine, a mold carrier, a mold having relatively adjustable parts forming between their molding faces the slug space, a sectional flexible liner movable into the slug space, and a housing adjacent the mold for containing sections of the liner.
- 35 13. In a device of the character described, a slug casting mold having relatively adjustable parts, and a series of liners in position to enter between said mold parts, means for moving any number of said liners between said mold parts, the number depending upon the separation of said parts.
- 40 14. In a device of the character described, a slug casting mold comprising a slug space, a flexible liner, a housing for said liner, and means for moving a predetermined length of said liner from said housing to said slug space.
- 45 15. In a device of the character described, a slug casting mold, having relatively adjustable parts, a flexible liner, a housing for said liner, and means for moving a predetermined length of said liner between the mold parts.
- 50 16. In a device of the character described, a slug casting mold having relatively adjustable parts, liners, and means performing to selectively put the liners between the mold parts.
- 55 17. In a device of the character described, a mold carrier, a slug casting mold having relatively adjustable parts, flexible liners carried by said carrier, said liners being of different gage, and means for moving the liners between the mold parts.
- 60 18. In a device of the character described, a slug casting mold, a mold carrier, a flexible liner, means for entering the liner into the mold, and means for deflecting any unentered portion of the liner from projecting beyond the periphery of the carrier.
- 65 19. In a device of the character described, a mold carrier, a slug casting mold having relatively adjustable parts, flexible liners carried by said carrier, and means for putting the liners between the mold parts and means for varying the number of liners put between said mold parts, the number depending upon the separation of the mold parts.
- 70 20. In a device of the character described, a slug casting mold having relatively adjustable parts, liners, and means one for each liner for putting the liners between the mold parts, the number put between said mold parts depending upon the separation of the mold parts.
- 75 21. In a device of the character described, a slug casting mold having relatively adjustable parts, a series of liners, and a series of elements, means for selectively engaging said elements with said liners, the number engaging depending upon the separation of the mold parts, and means for introducing said number of liners between the mold parts.
- 80 22. In a device of the character described, a slug casting mold having relatively adjustable parts, a series of liners, a series of elements, means for selectively engaging said elements with said liners, the number engaging depending upon the separation of said mold parts, and means for introducing said liners between the mold parts, the liners not engaged by said elements remaining outside said mold parts.
- 85 23. In a device of the character described, a slug casting mold having a fixed part and an adjustable part, liners arranged to enter between the mold parts, the adjustable mold part preventing entry of liners in excess of mold separation, and elements for inserting the liners between the mold parts, the fixed mold part preventing operation of said elements in excess of mold separation.
- 90 24. In a device of the character described, a slug casting mold having a fixed part and an adjustable part, liners arranged to enter between the mold parts, elements for inserting the liners between said mold parts, a mount for the elements, and said mount and adjustable mold part being movable together to simultaneously adjust the slug space and to determine the number of liners which may be inserted in said slug space.
- 95 25. In a device of the character described, a linotype mold having a fixed part and an

- adjustable part, a plurality of liners movable between said mold parts, a plurality of selective means for moving a variable number of said liners between said mold parts, a trimming mechanism comprising a fixed and an adjustable jaw, a connection between said adjustable part and adjustable jaw, and means for varying the number of liners moved by said means.
- 10 26. In a device of the character described, a slug casting mold having a fixed part and an adjustable part, liners therefor, a slug trimmer having an adjustable blade, means for adjusting the adjustable mold part, means for inserting the liners between the said mold parts carried by the means for adjusting the adjustable mold part, the adjustment of said mold part adjusting means being determined by the adjustment of the said adjustable blade and means for adjusting the adjustable blade.
- 15 27. In a device of the character described, a slug casting mold having relatively adjustable parts, liners therefor, means for putting the liners between said mold parts in numbers depending upon the separation of the mold parts, means for adjusting one of the mold parts, and means for moving the said first named means by said second named means.
- 20 28. In a device of the character described, a slug casting mold having relatively adjustable parts, liners, and a plurality of means operative in number depending upon the separation of the mold parts for putting a corresponding number of liners between the mold parts, and means for adjusting one of the mold parts.
- 25 29. In a device of the character described, a slug casting mold having a fixed part and an adjustable part forming between them the slug space, liners adapted to enter said slug space, means operative in proportion to the separation of the mold parts for putting a corresponding proportion of liners into the slug space, a slug trimmer having an adjustable blade, and means effecting cooperative adjustment of the blade and adjustable mold part.
- 30 30. In a device of the character described, a slug casting mold having a fixed part and an adjustable part forming between them the slug space, means for adjusting the adjustable mold part, liners adapted to enter the slug space, and means movable along said means for inserting liners in said slug space.
- 35 31. In a device of the character described, a slug casting mold having a fixed part and an adjustable part, and a spring pressed semi-nut and a screw for locking the adjustable mold part.
- 40 32. In a device of the character described, a slug casting mold having a fixed part and an adjustable part, a spring pressed semi-nut and a screw for locking the adjustable mold part, and means having a step adjustment coincident with the ratchet locking device for locking and unlocking said means and adjusting said adjustable mold part.
- 45 33. In a device of the character described, a slug casting mold having relatively adjustable parts, a series of liners in position to enter between said parts, and means adapted to enter any one of the liners between the mold parts.
- 50 34. In a device of the character described, a linotype mold having relatively adjustable parts, a plurality of liners in position to enter between said parts, and means adapted to enter any number of said liners between said parts.
- 55 35. In a device of the character described, a linotype mold having relatively adjustable parts, a plurality of flexible liners, a housing for said liners, means for selectively moving said liners between said mold parts and means for withdrawing said liners therefrom.
- 60 36. In a device of the character described, a linotype mold having a fixed part and an adjustable part, a plurality of liners movable between said mold parts, a plurality of selective means for moving a variable number of said liners between said mold parts, the number depending upon the separation of said parts, a trimmer comprising an adjustable blade and means effecting a simultaneous adjustment of said adjustable part and blade.
